UNITED STATES PATENT OFFICE.

OTTO S. BEYER, OF CARLSTADT, NEW JERSEY, ASSIGNOR TO BORDEN'S
CONDENSED MILK COMPANY, OF NEW YORK, N. Y.

BOTTLE-FILLER.

SPECIFICATION forming part of Letters Patent No. 668,303, dated February 19, 1901.

Application filed April 27, 1900. Serial No. 14,562. (No model.)

To all whom it may concern:

Be it known that I, OTTO S. BEYER, a citizen of the United States, and a resident of Carlstadt, in the county of Bergen and State of New Jersey, have invented certain new and useful Improvements in Bottle-Fillers, of which the following is a specification.

My invention provides a bottle-filler which operates to fill the bottle expeditiously and automatically, to prevent an accumulation of foam, and to reject bottles the edges of whose necks are so badly chipped as to prevent sealing by the ordinary temporary seals which do not extend down into the neck of the bottle.

15 My invention provides also a bottle-filler having various other advantages, which will be set forth in the following description.

In the accompanying drawings, which illustrate one embodiment of my invention, Figure 1 is a central vertical section showing the parts in the position immediately before operation. Fig. 2 is a similar section of the filling-tube and bottle in the operating position. Fig. 3 is a section on the line 3-3 of Fig. 2. 25 Figs. 4, 5, and 6 are central vertical sections and a horizontal section, respectively, of a modification; and Fig. 7 is a central vertical section of another modification.

The principal elements of the embodiments shown are a tank or similar receptacle and a vacuum-chamber, preferably in one, of which the lower portion forms the receptacle and the upper portion the vacuum-chamber, a pair of tubes one of which opens into the vacuum 35 for conducting the air from a bottle into said vacuum and the other of which opens into the liquid for conducting the same into the bottle from which the air is being exhausted, the outer ends of said tubes being adapted to be connected to the mouth of a bottle, means for sealing said bottle from the atmosphere, and valves in said tubes opened by the pressure of the bottle against the outer ends of said tubes.

40 Referring to the drawings, A indicates a tank the lower portion of which constitutes a liquid-receptacle, the level of the liquid being determined in any suitable manner, as by the well-known float-valve a. For the purpose of maintaining a vacuum in the vacuum-chamber—in this case the upper part of said

tank—I provide any suitable means, such as a pipe a', leading to any form of vacuum-pump.

As a means of supporting the bottle and 55 pressing the mouth thereof against the outer ends of the tubes I show a stand M, having a hub m. A plate H has a depending leg h, which passes through the hub m. A treadle-lever L bears upward on the under side of a 60 knob K, which has a pin k' entering the hollow interior of the leg h. A spring k is interposed between the top of the pin k' and the solid portion of the leg h. Downward pressure on the outer end of the lever L throws 65 up the knob K and pin k'. The latter acts with a spring-pressure to lift the plate H and with it the bottle G.

The two tubes which form the air-withdrawing and liquid-admitting means are preferably made concentric and connected with each other. In the present case the liquid-tube (designated as a whole as B) is composed of an upper portion b² and a lower portion b, connected in any suitable way, as by 70 brazing. The upper portion b² carries at its upper end a perforated plate b', preferably screwed thereinto, as shown, and having an interiorly-screw-threaded hub b¹⁴, preferably thickened for greater rigidity. The lower 75 portion b of the air-tube has a screw-threaded portion b³ and a polygonal flange b⁴, whereby it is connected with the lower plate a² of the liquid-receptacle. It also has one or more openings b⁵, communicating with the interior 80 of the receptacle. The lower end of the portion b is a plain cylinder. The air-tube, (designated as a whole by C,) in the present case the inner one of the two concentric tubes B and C, is provided near its upper end 85 with a diaphragm or piston c, which closes the annular space between the inner and outer tubes and in the preferable form (shown in Fig. 2) carries at its upper end a portion c', opening outwardly through openings c². On 90 the lower end of the tube C is brazed a spider c⁴. (Shown most clearly in Fig. 3.) On the lower end of said tube C is screwed or otherwise fastened a tube c⁵, which forms a continuation of the interior of the main tube C, 95 but which is outwardly flanged, as at c⁶, to form a valve member.

For the purpose of closing the lower end of the annular space between the two tubes I provide a closure D of any convenient type, in this case having an end portion d', the lower end of which is formed with a valve-face d², adapted to coact with the flange or valve member c³ on the inner tube to close said annular space. Said member D has an upward extension d surrounding the lower portion b of the outer tube on all sides. A spring E surrounds the member D, bearing at its upper end on the under side of the flange b⁴ and at its lower end on the outward flange d⁴ of the closure D and tending normally to press the valve-face d² against the valve member c³, and thereby close the outer tube. A shoulder d³ on the inner plate of the closure D limits the extreme upward movement of said closure by bearing against the lower end 20 of the tube B.

On the lower end of the closure D is a packing F of yielding material, such as rubber, made of such softness that when the edge of the bottle-mouth is pressed against it with sufficient force to lift the closure D its full stroke the packing material will fill up and close any small nicks in the mouth of the bottle, which would not interfere with the sealing of the same, but will not close any serious nicks, such as shown at y in Fig. 5, which would prevent the proper sealing of the bottle by the ordinary temporary seals in use.

For closing the inner tube C, I use a valve arranged, preferably, as shown in Figs. 1 and 2, in which c⁶ is a valve seating against an inner face on the hollow valve member c³ and held in a fixed position by a stem c⁷, brazed thereon and extending throughout the length of the tube C and screwed into the hub b¹⁴ on the top of the outer tube. The stem c⁷ and valve c⁶ are provided with means for unscrewing them, such as the polygonal socket c⁸ in the face of the valve. The upper part of the member c⁶ is formed into a guiding-spider c¹⁶.

A special point of usefulness of the construction described is the facility with which its individual parts may be separated, so as to be efficiently and easily cleaned. For this purpose the tube is first taken out of the tank by unscrewing the joint b³ by means of a wrench on the polygonal flange b⁴. The stem c⁷ is then unscrewed from the hub b¹⁴ by means of a wrench and the polygonal socket c⁸. The valve c⁶ being then withdrawn, the inner tube C and closure D may be removed together or separately by unscrewing the lower end c⁵ of the inner tube and removing it and its valve member c³.

The operation of my bottle-filler is entirely automatic, being accomplished by a pressure of the bottle's mouth against the packing F.

The operation of the embodiment above described is as follows: The parts being in the position of Fig. 1, the reservoir containing the desired quantity of milk, and there being in its upper portion a partial vacuum,

the spiral spring E bears down on the flange d⁴ around the lower end of the closure, so as to bring the valve-seat d² against the face of the valve c³ on the lower end of the inner tube. The same pressure holds the inner seat of c³ down on its valve c⁶ at the lower end of the rod c⁷. Both valves are thus held closed. The bottle is then placed in position 75 with its mouth against the packing F and is pressed upward. If the edge of the bottle-mouth be free from large nicks, the upward pressure closes it air-tight. As the pressure increases the spring E is compressed and the valve-seat d² lifted from the valve c³, opening the outer tube. The liquid will not run, however, unless its specific gravity and the distance of its level above the bottom of the tube be such as to make up the difference in 80 pressure between the atmosphere and the vacuum, which will not usually be the case. The continued upward movement of the bottle against the action of the spring E now brings the upper edge d³ against the under edge of 90 the spider c¹ on the inner tube, lifting the latter, and with it the valve c³. The air in the bottle now rushes through the inner tube up to the vacuum, increasing the pressure there (in proportion to the volume of the 95 vacuum-chamber, but preferably slightly) and greatly reducing the pressure in the bottle till the liquid flows downward and fills the latter. The action is very rapid, the air and the liquid assisting each other in assuming 100 the position of equilibrium, with the liquid at the bottom and all the air at the top. The bottle is then lowered, the air-valve c⁶ c³ closing first to prevent any possible loss of vacuum or dripping of the liquid and then the liquid-valve c³ d². The liquid taken from the tank has been replaced by an equal volume of air from the bottle, leaving the vacuum practically the same as before. If the float-valve shown be used, an equal volume of liquid 110 also enters after each bottle is filled, and the vacuum must be maintained by continuous pumping.

An important advantage of my device is that it selects imperfect or badly-nicked bottles and refuses to fill them, and by varying the softness of the packing F and the consequent depth to which the edge of the bottle sinks in it the standard of selection may be varied. If by pressing the bottle 115 with the full movement of the closure D there be still some nicks, such as y, Fig. 5, in the edge which are not closed by the packing, the air rushes in and maintains approximately atmospheric pressure in the bottle in spite of the 120 open passage to the vacuum. The liquid therefore is held up and none enters the bottle. But an instant is necessary to indicate the state of affairs to the workman, who releases the pressure on the treadle-lever and substitutes another bottle for the useless one. This function of the machine is particularly useful in filling bottles which are to be subsequently sealed for a short time by means which do 125 130 135

not extend down into the neck of the bottle, and which seal would be made ineffective by large nicks in the edge. In such case the packing F of my apparatus is of such softness that it seals the bottle and admits liquid thereto only when its edge is substantially unbroken, so as to be capable of being subsequently sealed, as explained, and is prevented from sealing or filling the same if the bottle has breaks of any considerable size along its edge, so as to make such subsequent sealing impossible.

With liquids which have a tendency to foam my apparatus is particularly useful. Bubbles when formed rise immediately in the inner tube and are broken by reason of the excess of pressure within them over that in the vacuum-chamber and inner tube.

As soon as the inner valve is closed in withdrawing the bottle liquid which may be in either tube is held there by the valve c^6 and the suction of the vacuum. The tubes may therefore be as large as desirable without the occurrence of any dripping after the removal of the bottle. By placing the closure of the liquid-tube at the bottom and arranging the lower ends of both tubes substantially level with the edge of the bottle it results that the bottle is filled just to its edge. I thus avoid the presence of an air-space between the surface of the liquid and the seal which is subsequently applied. If, however, it be desired to have the liquid at a lower level, the end portion d' of the closure D and the valve members c^8 and c^6 may enter into the neck of the bottle to the point of the desired level of the liquid.

Though I have described an embodiment of my invention with great particularity of detail, yet I am not to be understood as limiting myself to the particular details and combinations shown, as various modifications thereof are possible without departing from the spirit of my invention. For example, I show in Figs. 4, 5, and 6 a construction substantially identical with that of Fig. 1 as to the liquid or outer tube and its valve, but having its inner tube C' of less diameter than in the previous construction, thereby obtaining a greater space between the two tubes for the flow of the liquid, and utilizing the capillarity of the inner tube to prevent any drip. The air-valve in this case is at the top, and comprises a seat b^{10} on the top of the outer tube and a valve proper, c^{10} , on the inner tube, the valve being opened, as in the construction of Fig. 1, by the upward movement of the inner tube after the outer tube-valve has been opened and the shoulder d^8 on the lower closure has come into contact with the spider c^4 . A piston or diaphragm c^{11} , brazed on the upper end of the tube C', closes the annular space between the tubes, and the upper end c^{12} of the inner tube is preferably a separate piece screwed into the main portion of the tube and provided with a polygonal socket at the top for unscrewing it and with orifices c^{13} , opening into the annular space

above the piston c^{11} and thence through the valve c^{10} to the vacuum-chamber. Fig. 5 shows the air-valve open and the action of the filler when it is attempted to fill a bottle which it would be impossible to seal, as explained. The arrows show the atmospheric air passing into the vacuum-chamber without reducing the pressure in the bottle.

Fig. 7 shows a further modification, in which a valve b^{11} is suspended by a rod b^{12} from a plate b^{13} , which may be identical with the plate b' of Fig. 2. The valve-seat c^{14} in the present case is on the inner tube and is attached by a cylindrical extension c^{15} to the diaphragm c^{16} on the upper end of the inner tube C'. The operation is the same as for the other constructions.

What I claim, therefore, and desire to secure by Letters Patent, are the following-defined novel elements and combinations, all substantially as shown and described:

1. The combination in a bottle-filler of means for withdrawing air from said bottle and means for admitting liquid thereto, the air-withdrawing means being operative after the liquid-admitting means has ceased its operation.

2. The combination in a bottle-filler of means for withdrawing air from said bottle, means for admitting liquid thereto, a reservoir for said liquid, means for maintaining a vacuum in said reservoir and means for discharging the withdrawn air into said reservoir.

3. The combination in a bottle-filler of an air-tube, a chamber connected therewith, means for maintaining a vacuum in said chamber, a liquid-tube, a liquid-reservoir connected therewith, and means for connecting said tubes with a bottle.

4. The combination in a bottle-filler of an air-tube, a chamber connected therewith, means for maintaining a vacuum in said chamber, a liquid-tube, a liquid-chamber connected therewith, means for connecting said tubes with a bottle, and means for connecting said liquid-reservoir with said vacuum-chamber.

5. The combination in a bottle-filler of an inner tube, an outer tube supporting said inner tube and closing the same, and a closure for said outer tube supported by said inner tube.

6. The combination in a bottle-filler of an inner tube open at both ends, an outer tube open at one end and at an intermediate point, means for closing said inner tube, and means for closing the end of said outer tube.

7. The combination in a bottle-filler of an inner tube, an outer tube supporting said inner tube and closing the same, a closure for said outer tube supported by said inner tube, and means whereby the lifting of said closure lifts said inner tube, whereby the lifting of said closure opens both said tubes.

8. The combination in a bottle-filler of an inner tube, an outer tube, a valve member

for closing said inner tube and for supporting the said inner tube from said outer tube, a pair of shoulders on said inner tube, a head surrounding said inner tube and having vertical play between said shoulders, an upward extension from said head closing said outer tube laterally, and means for pressing said head against the lower one of said shoulders.

9. The combination in a bottle-filler of an outer tube carrying a valve member and open at its lower end and at an intermediate point, an inner tube having a diaphragm closing said outer tube at a point above its intermediate opening and having openings above said diaphragm, of a valve member carried at the lower end of said inner tube adapted to coact with the valve member on said outer tube to close said inner tube.

10. The combination in a bottle-filler of an outer tube open at its lower end, an inner tube slidable therein, a closure having sides fitting the sides of said outer tube so as to close the same and having a head surrounding said inner tube, a valve member on the lower end of said inner tube and a corresponding valve member on the lower part of said head to close the lower end of said outer tube.

11. The combination in a bottle-filler of means for withdrawing air therefrom and means for sealing said bottle against the admission of atmospheric air, the sealing means being adapted to seal said bottle when its edge is substantially unbroken, and to be prevented from sealing the same when said edge is broken.

12. The combination in a bottle-filler of means for withdrawing air therefrom and

means for sealing said bottle against the admission of atmospheric air, the sealing means being adapted to bear against the edge of the mouth of said bottle, whereby irregularities in said edge prevent the establishment of said seal.

13. The combination in a bottle-filler of an outer tube, an inner tube, and a valve member rigidly but detachably attached to one of said tubes for holding them together.

14. The combination in a bottle-filler of an outer tube, an inner tube, and a valve member c^6 rigidly but detachably attached to said outer tube and closing the lower end of said inner tube.

15. The combination in a bottle-filler of an outer tube, an inner tube, a valve member c^6 supported from said outer tube and closing said inner tube, a valve member c^8 supported from said inner tube and a closure D movable on said outer tube and coöperating with said valve member c^8 to close said outer tube.

16. The combination in a bottle-filler of an outer tube, an inner tube, a valve member c^6 supported from said outer tube and closing said inner tube, a valve member c^8 supported from said inner tube, and a closure D coöperating with said valve member c^8 to close said outer tube, said valve members c^6 and c^8 being detachable from their supports.

In witness whereof I have hereunto signed my name in the presence of two subscribing witnesses.

OTTO S. BEYER.
